UNITED STATES PATENT OFFICE.

HOWARD S. NEIMAN, OF BROOKLYN, NEW YORK.

TOILET DEVICE.

Application filed January 9, 1922. Serial No. 527,969.

To all whom it may concern:

Be it known that I, HOWARD S. NEIMAN, a citizen of the United States, residing in Brooklyn, county of Kings, city of New York, and State of New York, have invented certain new and useful Improvements in Toilet Devices, of which the following is a full, clear, and exact specification.

10 My invention relates to toilet devices and refers particularly to devices combining a mirror and a cosmetic.

15 The object of my invention is a mirror combined with a cosmetic carried in a holder as, for instance, so-called lip-sticks, eyebrow pencils, etc., in such a manner that the cosmetic holder is adapted to act as a handle for the mirror when the device is in use and can be folded, or revolved, into a position 20 transverse of the mirror when the device is not in use.

25 My invention includes also means for the retention of the cosmetic holder in its desired open and closed positions, means for preventing the accidental removal of the cosmetic from its container and other desirable and valuable elements, which will be evident upon a consideration of my specification and accompanying drawings.

30 In the accompanying drawings, illustrating one form of the device of my invention, similar parts are designated by similar numerals.

Figure 1 is a top plan view of one form 35 of my device, partly broken away, for purposes of clearer description.

Figure 2 is a side view of Figure 1.

Figure 3 is an enlarged end view of Figure 1, partly broken away for purposes of 40 clearer description.

The particular form of the device of my invention, shown in the accompanying drawings, comprises a base, or frame, 10, carrying a mirror 11 on one face thereof. 45 A pivotal member 12, having a head 13, is passed through the aligned openings 14 and 15 in the cosmetic stick cover 16 and through an opening 17 in the frame 10, the other extremity of the pivot 12 having the head 18. 50 The pivot 12 is fixedly attached to the underside of the frame 10 by means of solder 19 and thus acts as a pivot around which the cover 16 may be revolved.

Slidable within the cover 16 is a cosmetic

stick holder 20 having the head 21 and carrying the cosmetic 22. Slidable within the slot 23 of the holder 20 is a member 24 to which the cosmetic 22 is attached, and hence, can be forced outwardly of the holder as desired.

55 A guard 25 extends upwardly from the base 10 prevents the accidental removal of the cosmetic stick when the device is in closed position and allows of the movement of the cosmetic device in the direction of the arrow of Figure 1 while preventing its movement in the reverse direction.

60 A projection 26 in the holder 16 fits within the depressions 27 and 28, thus holding the cosmetic device in either of its revolved positions.

65 When it is desired to use the device, the cover 16 with its contents is revolved around the pivot 12 until it assumes the position 16' when the projection 26 enters the depression 28 holding the cover in a fixed position. 70 The cosmetic holder 20 with the cosmetic stick 22 is withdrawn from the cover 16 and the cover used as a handle for the mirror while the cosmetic is being used.

75 When the use of the cosmetic is finished, the holder may be replaced within the cover and revolved back into its original position, the projection 26 entering the depression 27, maintaining the cosmetic device in its revolved, or closed, position free from accidental movement, while the guard 25 maintains the cosmetic holder from accidental removal from the holder.

80 It is also evident that a plurality of cosmetic sticks, as, for instance, a lip-stick and an eyebrow pencil, may be employed as above described, and by "cosmetic stick cover" and "cosmetic stick," as used in my claims, I mean both a single and a plurality 85 of such covers and sticks.

I do not limit myself to the particular size, shape, number or arrangement of parts as shown and described, the accompanying drawings being shown simply for purposes 100 of clearer description of the device of my invention.

What I claim is:—

1. In a toilet device, in combination, a mirror frame, a mirror carried by the frame, 105 a cosmetic-stick cover positioned externally of the device, pivotal means connecting the cosmetic-stick cover and the mirror frame

whereby the cover may be revolved in a plane parallel to the plane of the frame and a cosmetic stick carried within the cosmetic-stick cover and capable of removal therefrom.

2. In a toilet device, in combination, a mirror frame, a mirror carried by the frame, a cosmetic-stick cover positioned externally of the device, pivotal means connecting the cosmetic-stick cover and the mirror frame whereby the cover may be revolved in a plane parallel to the plane of the frame, means for preventing the cover from accidental displacement and a cosmetic-stick carried by the cover and capable of removal therefrom.

3. In a toilet device, in combination, a mirror frame, a mirror carried by the frame, a cosmetic-stick cover, pivotal means connecting the cosmetic-stick cover and the mirror frame whereby the cover may be revolved in a plane parallel to the plane of the frame, a cosmetic-stick carried within the cosmetic-stick cover and a guard preventing the accidental removal of the stick from the cover.

4. In a toilet device, in combination, a mirror frame, a mirror carried by the frame, a cosmetic-stick cover, pivotal means connecting the cosmetic-stick cover and the mirror frame whereby the cover may be revolved in a plane parallel to the plane of the frame, means for preventing the cover from accidental displacement, a cosmetic-stick carried by the cover and a guard preventing the accidental removal of the stick from the cover.

ried by the cover and a guard preventing 35 the accidental removal of the stick from the cover.

5. In a toilet device, in combination, a mirror frame, a mirror carried by the frame, a cosmetic-stick cover, pivotal means connecting the frame and the cover, an extended member carried by the cover and a plurality of depressions in the frame capable of receiving the extended member.

6. In a toilet device, in combination, a mirror frame, a mirror carried by the frame, a cosmetic-stick cover, a cosmetic-stick carried by the cover capable of removal from the cover, pivotal means connecting the frame and the cover, an extended member carried by the cover and a plurality of depressions in the frame capable of receiving the extended member.

7. In a toilet device, in combination, a mirror frame, a mirror carried by the frame, a cosmetic-stick cover, a cosmetic-stick carried by the cover, pivotal means connecting the frame and the cover, an extended member carried by the cover, a plurality of depressions in the frame capable of receiving the extended member and a guard preventing the accidental removal of the stick from the cover.

Signed at New York city in the county of New York and State of New York this 65 7th day of January, 1922.

HOWARD S. NEIMAN.
